UNITED STATES PATENT OFFICE.

MOSES LALONDE AND JOHN A. SMEATON, OF SPRINGFIELD, MASSACHUSETTS.

TOILET-PAPER HOLDER.

Application filed January 17, 1923. Serial No. 613,182.

To all whom it may concern:

Be it known that we, MOSES LALONDE, a subject of the King of England, and JOHN A. SMEATON, a citizen of the United States 5 of America, and both residents of Springfield, in the county of Hampden and State of Massachusetts, have invented a new and useful Toilet-Paper Holder, of which the following is a specification.

Our invention relates to improvements in devices or appliances for holding toilet paper, and more especially to holders of this character which are capable of dispensing the paper as well as holding the same, and 10 consists essentially of a supporting body provided with a bail, a paper feeder carried by said bail, and means attachable to said body and adapted to support the direct supporting or suspension means for the 15 toilet paper, either when the latter is in roll formation or flat package formation, together with such other parts and members as may be necessary or desirable in order to render the holder complete and serviceable in every respect, all as hereinafter set forth.

The primary object of our invention is to produce a comparatively simple and inexpensive appliance for both holding and 20 dispensing toilet paper of either type, that is to say, toilet paper in the roll or flat toilet paper in the package.

A further object is to provide a holder of this character with convenient means for 25 feeding paper from a roll, or for feeding paper one sheet at a time from a package. The feeding operation preferably involves merely the starting of the leading end or sheet of paper downwardly into a position 30 where it can be readily grasped and either torn off or drawn clear of the package and holder.

The body of the holder is provided with a blade against which the paper can be 35 conveniently torn off from the strip above when fed down from a roll. Such blade is not needed when the holder is used for flat paper, and may then be removed if desired.

Other objects and advantages will appear 40 in the course of the following description.

We attain the objects and secure the advantages of our invention by the means illustrated in the accompanying drawings, in which—

Figure 1 is a front elevation of a toilet-

paper holder which embodies a practical form of our invention, such holder being supplied with a roll of toilet paper; Fig. 2, a central, transverse, vertical section through said holder and roll; Fig. 3, an enlarged detail of one of the connections between the bail and the feed-block guide; Fig. 4, an enlarged, side elevation of the roller which we prefer to use in connection with our holder when toilet paper in rolls 60 is to be carried and dispensed thereby; Fig. 5, a sectional detail of the upper part of the holder illustrating the supporting means for a package of flat toilet paper, and, Fig. 6, a front end elevation of the rod which forms 65 a part of such supporting means.

Similar reference characters designate similar parts throughout the several views.

In the preferred embodiment of our holder, as illustrated in connection herewith, 70 the same comprises a sheet-metal body consisting of a plate 1 in front, and a rearwardly-extending flange 2 which forms top, bottom, and side pieces to rest against a wall, and with said plate to enclose certain 75 parts presently to be described. A vertical slot 3 is formed in the plate 1 near the top, and the portion of said plate which is struck out to form said slot extends rearwardly from the bottom edge of said slot, and has 80 a depression formed therein to produce a cupped lug 4. Flanking the slot 3 are two slots 5 in the plate 1, and the material struck out of said plate to form such slots extends 85 rearwardly from the bottoms thereof to produce a pair of engaging lugs for a bail 6, one of such lugs appearing at 7 in Fig. 2. Each lug 7 has the rear end bent upwardly and forwardly in the shape of a hook to engage the rear reach of the bail 6. In each 90 side piece of the flange 2 is a recess or indentation, as clearly shown at 8 in Fig. 5. The axes of the indentations 8 and the hooked portions of the lugs 7 are in a straight horizontal line, and the aforesaid 95 rear reach of the bail 6 is received in said indentations and hooks. The indented portions of the flange 2 afford the necessary bearing for the bail 6, and the hooked lugs 7 prevent said bail from becoming accidentally disconnected from such bearings.

The bail 6 consists of the reach of which mention has been made, a pair of side arms, and inwardly-extending parts from the forward terminals of such arms, said parts 100 105 110

being in line with each other and parallel with said reach. Each free end of the bail 6 is shouldered, as best shown at 9 in Fig. 3. The bail may be freely swung up and down with the rear reach rocking in the indentations 8 and the hooked portions of the lug 7.

A feeder guide is represented at 10, and the same consists of a plate and two rear-wardly-extending side pieces. Each of the side pieces of the guide 10, intermediate of its ends is struck outwardly, as shown at 11 in Figs. 1 and 3, and perforated to receive one of the free terminals of the bail 6. Each shoulder 9 on the bail 6 and the contiguous outwardly-projecting bearing part 11 prevent the corresponding free terminal of said bail from entering said bearing part far enough to interfere with the movement of a feeder which is designed to be moved up and down in the guide 10 between the sides thereof. The guide 10 may be moved with the bail 6 and also rocked independently thereon. There is a vertical slot 13 in the center of the guide 10. The feeder comprises a block 12, and abrading material, such as a piece of sandpaper 14, on the back side of said block. A knob 15 has a shank 16 that extends through the slot 13 and is tapped onto the block 12. The shank 16 can be moved up and down in the slot 13 by means of the knob 15, and when so moved said shank carries with it the block 12. The combined thickness of the block 12 and the sandpaper 14, which constitute the feeder, is less than the width of the sides of the guide 10, consequently said feeder can be drawn away from the plate 1 or paper thereon, by means of the knob 15, without disturbing said guide.

In Figs. 1 and 2, a vertical support in the form of a rod 17 is provided. The rod 17 has on the front side at the top a hook 18. There is a hole 19 in the top piece of the flange 2, which hole is directly above the cupped portion of the lug 4, and the rod 17 is passed downwardly through said hole onto said lug, being thereby supported in a vertical position. A second bail 20, has its rear or upper reach provided with an intermediate eye 21 that is receivable on the hook 18. The free terminals of the bail 20 are receivable in opposite ends of a roller 22. On the roller 22 is mounted a roll 23 of toilet paper. The rod 17 and bail 20 support the roller 22 and the roll 23 in position for said roll to bear against the face of the plate 1 a short distance below the upper edge thereof. The roll 23 is arranged on the roller 22 in such a manner as to enable the paper from said roll to be drawn off from the back side of the roll. The strip of paper from the back side of the roll 23 passes downwardly against the face of the plate 1, as represented at 24. Upper and

under guide bars 25 and 26, respectively, may be attached to the supporting body in such a manner as to enable the strip 24 to pass between the plate 1 and said bars. Ordinarily the guide bar 25 can be dispensed with, but the guide bar 26 also serves as a blade for the paper, and is necessary when the holder is used with roll toilet paper. The guide or blade 26 is not needed for flat toilet-paper and may be omitted altogether or removed from the body of a holder which is to be used exclusively for flat toilet paper. In the present case the terminals of the bars 25 and 26 are bent rearwardly and attached to the side pieces of the flange 2. There must, of course, be sufficient clearance back of the bars 25 and 26 for the paper.

Inasmuch as different toilet-paper rolls differ to a greater or less extent, we prefer to provide the roller 22 with three bow springs 27. The springs 27 extend longitudinally of the roller 22, they are arranged equidistant apart, and one terminal of each is secured to said roller. Thus the roller 22 is adapted to fit the passage through any paper roll, and frictionally engage such roll so that the elements rotate together.

In practice, the roller 22 is thrust through the toilet-paper roll 23, the free terminals of the bail 20 are sprung apart to enable the inwardly-directed parts of such terminals to enter into engagement with the ends of said roller, and the paper is drawn downwardly from said roll and passed through the bars 25 and 26, the knob 15 being grasped and the feeding members swung upwardly with the bail 6 to enable the paper to be passed downwardly against the face of the plate 1, or to facilitate such operation. After the paper strip 24 is in readiness for feeding, the feeding members are permitted to swing back again with the guide 10 resting against said strip. The strip 22 is now left with a portion of the same projecting below the bar or blade 26. This projecting portion is grasped with the hand and drawn downwardly until the required length below said bar is obtained, when the same is torn off against the bottom edge of said bar. After this, in order to obtain the next sheet or piece of paper, grasp the knob 15 and move the block 12 forwardly a sufficient distance to enable the sandpaper 14 to clear the strip 24, carry said block upwardly, move said block rearwardly to press said sandpaper against said strip, and carry said block downwardly. This last action causes the strip 24 to be carried downwardly with the sandpaper 14, and the extent of the movement is sufficient, provided the same be commensurate with the length of the slot 13, to cause a portion of said strip to project below the bar 26. This projecting portion of the paper is long enough to enable it to be grasped between the thumb and finger.

When the aforesaid projecting portion of the paper is grasped, the strip is drawn downwardly until the required length appears below the blade 26, and then the same 5 is torn off against said blade. These operations are repeated until the roll 23 is exhausted, when the roller 22 is supplied with a new paper roll.

The bail 20 and roller 22 are not, of course, 10 required for flat toilet paper, hence they are laid aside or not provided at all when the holder is to be used for such paper. The vertical rod 17 must also be discarded for an angular and generally horizontal support or 15 rod 28—see Figs. 5 and 6. The rod 28 has a downwardly-extending rear part which is receivable in the hole 19 and on the lug 4, and a downwardly-extending front part which forms a hook 29. When the rod 28 is in 20 place, the bottom of the space between the parts which form the hook 29 is approximately on a level with the top of the lug 4.

In Fig. 5, the upper portion of a package 25 of flat toilet paper is represented at 30, and a binder wire for such package at 31. The wire 31 has an eye 32 at one end as usual. The package 30 is connected with and supported by our holder by introducing the wire eye 32 through the slot 3 in the plate 1 onto 30 the lug 4, passing the vertical, rear part of the rod 28 downwardly through said eye onto said lug, and placing the forward-terminal portion of said wire in the hook 29, the wire preferably being bent over in front of said 35 hook. Thus the package 30 is securely held in place in readiness for the action thereon of the feeder.

The bail 6 enables the guide 10 to be placed 40 against the front sheet of the package 30, and always to gravitate against said package, just as it gravitates against the strip 24 in the other case. The block 12 is manipulated by means of the knob 15, to detach one sheet after another from the package 30, in the 45 same manner that it is operated for the purpose of moving the strip 24 downwardly. The block 12 should be elevated sufficiently and moved downwardly the required distance to enable the sandpaper 14, not only to engage and loosen the foremost sheet of 50 paper on the wire 31, but to tear away and detach such sheet entirely from said wire, although the sheet could without difficulty be torn loose even if it were only partially detached by the feeder. Each sheet, as it is fed downwardly by the block and sandpaper, is left with its lower portion projecting below the bottom of the package 30 and even 55 below the bottom of the holder, consequently in position to be readily grasped between the thumb and finger and withdrawn completely from between the other sheets or package and said sandpaper.

After the package 30 is exhausted, the rod 60 28 is raised to release the binder wire 31, the

latter is removed, and the binder wire of a fresh package is mounted in place in the holder.

The roller 22 may have recesses in the ends to receive the free ends of the bail 20, and 70 said roller is shown broken away to show one such recess at 33 in Fig. 4.

The use of this holder is not necessarily restricted to toilet paper.

More or less change of shape, size, construction, and arrangement of some or all of the parts of this holder, in addition to those hereinbefore specifically pointed out, may be made without departing from the spirit of our invention or exceeding the scope of what 75 is claimed.

What we claim as our invention, and desire to secure by Letters Patent, is—

1. The combination, in a holder of the class described, with a body provided with a 80 movable bail, a guide movably mounted on said bail, and a feeder slidingly arranged in said guide, of means to support paper in operative position relative to said feeder.

2. The combination, in a holder of the 85 class described, with a body provided with a movable bail, a slotted guide pivotally connected with said bail, and an abraded feeding block in said guide, said block being provided with an operating member therefor 90 which extends through the slot in said guide, of means to support paper in operative position relative to said guide and block.

3. The combination, in a holder of the 95 class described, with a sheet-metal body 100 comprising a front plate and indented side pieces, hooked lugs struck out of said plate, a bail receivable in the indentations in said side pieces, and in the hooked parts of said lugs, and paper-feeding means carried by 105 said bail, of means to support paper in operative position relative to said feeding means.

4. The combination, in a holder of the 110 class described, with a body provided with means to support a rod in an approximately vertical position, and a rod capable of being upheld by said means and projecting above said body, of a bail pivotally connected with said body, and paper-feeding means carried by 115 said bail, said rod being adapted to support paper in feeding position in relation to said paper-feeding means.

5. The combination, in a holder of the 120 class described, with a sheet-metal body comprising a front plate and a perforated top piece, a portion of said plate being struck out to leave an opening and form a lug, and the perforation in said top piece being above 125 said lug, and a rod receivable in said perforation and by said lug, and adapted to support paper in feeding position of a bail pivotally connected with said body, and paper-feeding means carried by said bail.

6. The combination, in a holder of the 130 class described, with a sheet-metal body com-

prising a front plate and a perforated top piece, portions of said plate being struck out to form lugs, and the perforation in said top piece being above one of said lugs, and 5 a rod receivable in said perforation and by the lug below the same, and adapted to support paper in feeding position of a bail pivotally connected with said body and held in such connection by the others of said lugs, 10 and paper-feeding means carried by said bail.

7. The combination, in a holder of the class described, with a sheet-metal body comprising a front plate and top and side pieces, 15 portions of said plate being struck out to form lugs, said top piece having an opening therein above one of said lugs, and said side pieces being recessed, of a rod receivable in said opening and by the lug below the 20 same, and adapted to support paper in feeding position a bail receivable in said recesses and adapted to be held therein by the others of said lugs, and paper-feeding means carried by said bail.

25 8. The combination, in a holder of the class described, with a body, a bail pivotally connected therewith, a slotted guard pivotally mounted on said bail, and having side pieces to support the same against said body or interposed paper, and an abraded feeder 30 block provided with a projecting member which extends through the slot in said guard, said block being of less thickness than the breadth of said side pieces, of 35 means to support paper in operative position relative to said guide and block.

9. The combination, in a holder of the class described, with a body having rod-supporting means, and provided with a movable 40 bail, and feeding means carried by said bail, of a rod adapted to be supported by said first-named means, a second bail carried by said rod, and a roller for paper carried by said second bail.

45 10. The combination, in a holder of the class described, with a body having rod-supporting means, and provided with a movable bail, paper-feeding means carried by said bail, and paper-guide members connected 50 with said body above and below said feeding means when in operative position relative to paper interposed between said body and

said feeding means, one of said members serving as a blade against which to tear the paper, of a rod carried by said first-named means, a second bail carried by said rod, and a roll for paper carried by said second bail. 55

11. The combination, in a holder of the class described, with a body comprising a front plate and a top piece, said plate having a part cut out to form a lug, and said flange having an opening therein above said lug, a bail pivotally connected with said body, and paper-feeding members pivotally connected with said bail, of a rod receivable 60 in said opening and on said lug, said rod having bail-engaging means, a second bail adapted to be connected with said means, and a roller carried by said second bail. 65

12. The combination, in a holder of the class described, with a body consisting in part of a front plate and a perforated top piece, said plate being cut out to leave a slot and form a lug, and the perforation in said top piece being above said lug, a bail movably connected with said body, and paper-feeding means carried by said bail, of a hook-provided rod having one terminal receivable in said perforation and on said lug such rod being maintained in an approximately vertical position by the perforated part of said top piece, and adapted to support paper in operative position relative to said paper-feeding means. 70 75 80

13. The combination, in a holder of the class described, with a body consisting in part of a front plate and a perforated top piece, said plate being cut out to leave a slot and form a lug, and the perforation in said top piece being above said lug, a bail movably connected with said body, and paper-feeding means carried by said bail, of a rod having a part to enter said perforation and rest on said lug behind said slot, and having a part to receive the forward terminal portion of the binder wire of a package of toilet paper, while the eye of said wire is engaged by said first-named part of said rod, after said eye is passed through said slot. 85 90 95
